UNITED STATES PATENT OFFICE.

BERNARD CHARLES HOWELL, OF LONDON, ENGLAND, ASSIGNOR TO HENRY HOWELL & COMPANY LIMITED, OF LONDON, ENGLAND, A BRITISH COMPANY.

SMOKER'S COMPANION.

Application filed March 23, 1926, Serial No. 96,851, and in Great Britain February 20, 1926.

This invention consists in improvements in or relating to smokers' companions, ash-trays, match-and-cigarette-containers and like smokers' requisites. Hereinafter, and in 5 the appended claims, all these articles will be referred to, for the sake of brevity, by the term "smoker's companion"; and it is to be understood wherever this term appears that it is intended to refer to any of the articles enumerated, or like articles.

The present invention comprises, in one form, the combination of a hollow ornamental figure, a portion of which is translucent, an electric lamp serving to illuminate 15 the interior of the hollow figure, an energizing circuit for the lamp, and a switch-device for said energizing circuit, said switch-device comprising a movable match-striking surface so that when a match is struck on it 20 the circuit of the lamp will be closed and the lamp will be illuminated.

In order that the invention may be more clearly understood, one preferred construction embodying the features of the invention, 25 will now be described with the aid of the accompanying drawings, in which—

Figure 1 is a perspective view of a "smoker's companion";

Figure 2 is a plan of the underside of the 30 hollow base of the companion with the cover removed, and

Figure 3 is a section on the line 3—3 of Figure 2.

Like reference numerals indicate like parts 35 in all the figures of the drawings.

It will be seen that a hollow base member 10 serves to contain within it a battery 11 (Figures 2 and 3) of the dry cell type which is held in position by means of clips 40 12 constituting terminal-connectors through which the battery is connected in electric circuit to be detailed hereinafter. The base-member 10 supports on its upper surface an ash-tray 13 and a receptacle 14 for containing loose matches. In addition to these articles, and normally flush with the upper surface of the base-member 10, there is a spring-pressed switch-button 15, the outer surface 45 of which is provided with a match-striking composition preferably of a character suitable to the so-called safety matches as well as to those of the non-safety type.

Supported also on the base-member 10 is an ornamental Figure 16 which, in the illustrated example, is shaped to represent an owl.

The eyes 17 are formed of translucent material such, for example, as coloured glass or a translucent composition. The body of the owl, as seen in Figure 3, is hollow and is open at the lower end. The latter is received 60 in a socket in the top wall of the base and an incandescent electric lamp 18 is supported in any preferred manner within the body of the owl, preferably at the level of the eyes 17. In the particular example shown, the 65

current-carrying conductors 19, which pass through the hollow interior of the Figure 16 and through the socket in which the owl is seated in the base 10, serve not only to convey the energizing current to the lamp 18 70 but also to support the latter at the required height.

In the interior of the base 10 is disposed the wiring which connects the switch-contacts (operated by the button 15) and the 75 battery with the conductors 19. The circuit for the wiring is clearly shown in Figures 2 and 3 from which it will be seen that one pole of the battery 11 is electrically connected to a contact-stud 20 which can be engaged by a metal under surface of the button 15, which metal surface is constituted as part of a spring strip 21 electrically connected to one of the conductors 19 and normally tending to retain the switch in its open 80 position. The other conductor 19 is electrically connected with the other pole of the battery respectively with the contact stud 20 and one of the conductors 19 is effected by 85 means of the spring clips 12 which also serve to hold the battery in position. It will, therefore, be seen that whenever a match is struck on the surface of the button 15, the circuit will be closed and the eyes will light 90 up which gives an impression rather as though the owl's eyes have blinked.

The parts contained within the base 10 can be enclosed by means of a cover-plate 22 which may be secured, for example, by 100 screws as shown or by any other preferred form of fastening.

It is obvious that details of the invention may be modified while still retaining the objects and benefits of the invention.

It is further obvious that the invention may be applied in many other ways. For example, the figure may be in the form of a cat or other animal and the switch-device may comprise a part of the body of the 110

animal which, when stroked by a match held in the hand, will cause the energizing circuit to be closed and the lamp to be illuminated.

I claim:—

- 5 1. In a "smoker's companion", the combination of a hollow ornamental figure, a portion of which is translucent, an electric lamp serving to illuminate the interior of the hollow figure, an energizing circuit for the lamp, and a switch device for said energizing circuit, said switch device comprising a movable match striking surface.
- 10 2. In a smoker's companion the combination of a hollow ornamental figure, a portion of which is translucent, an electric lamp serving to illuminate the interior of the hollow figure, an energizing circuit for the lamp, and a resiliently controlled button switch for said energizing circuit, one surface of said button comprising a match striking surface.
- 15 3. A smoker's companion comprising in combination, a hollow ornamental figure, a portion of which is translucent, an electric lamp situated within the interior of the hollow figure, an energizing circuit for the lamp, and a switch device for the energizing circuit, said switch comprising a match striking surface which is movable to close the
- 20 30 4. In a "smoker's companion" the combination of a hollow base member, a hollow

ornamental figure mounted on said base member and having a translucent portion, an electric lamp situated within the hollow figure, an energizing circuit for the lamp, a switch-device having a surface available from the outside of said base member and comprising a match-striking surface, and an electric battery which is retained within the base member and constitutes the energizing means for the circuit.

5. In a "smoker's companion", the combination of a hollow ornamental figure having translucent eyes, an electric lamp situated within said hollow figure, an energizing circuit for the lamp, and a switch-device comprising a movable striking surface.

6. In a "smoker's companion", the combination of a hollow base member, a hollow figure mounted on the base member which hollow figure is shaped to represent an owl having translucent eyes, an electric lamp situated within the body of said owl, an energizing circuit for the lamp, a resiliently controlled button switch for the energizing circuit, said switch having a surface available for use from the outside of the base member and comprising a match-striking surface, and an electric battery retained within said base member and constituting the energizing means for the said circuit.

In testimony whereof I affix my signature.
BERNARD CHARLES HOWELL.
